1 Claim

ABSTRACT OF THE DISCLOSURE

This invention relates to an improved form of shoe last, particularly of the molded type, wherein the improvement resides in the provision of an interchangeable front or toe portion whereby to permit an instantaneous conversion of the last configuration to conform with prevailing fashion trends affecting the shape or profile of the front of shoes.

The present invention relates to shoe lasts and particularly to an improvement in molded shoe lasts, the said improvement residing in the provision of means whereby to render the front or toe end of the last interchangeable.

It used to be that shoe lasts were made entirely from wood but in recent years molded plastic shoe lasts have gained acceptance in the shoe manufacturing trade and are increasing in popularity.

Conventionally, shoe lasts are composed of two principal parts which are connected for pivotal articulation of one with respect to the other about a transverse horizontal axis. The two principal parts being the heel portion and the front portion respectively. It is common practice for the manufacturers of shoes to periodically have to replace their entire stock of shoe lasts for the sole purpose of conforming to new and prevailing fashion trends which affect shoe configurations. Each time that such updating of lasts is made necessary, the manufacturers of shoes suffer heavy losses and it is particularly such losses which the present invention is intended to minimize.

Time after time, the only portion of the shoe configuration which is affected by changing fashion trends is the tip or front. In recent years, for instance, trends have variously called for shoes having pointed tips, blunt or square tips or tips that merely reflect the general profile of the toes. Such radical changes are particularly noticeable in the feminine footwear industry. Since the toe end portion of a shoe is the only part thereof the shape of which varies from time to time, it follows that it is also the shape of the corresponding front end of the last that truly requires to be modified accordingly each time.

The present invention takes advantage of the aforementioned practical observation in presenting means whereby it becomes possible for manufacturers of shoes to modify their existing sets of shoe lasts by merely replacing the toe portion thereof by another toe portion which is more appropriately shaped to conform with a new fashion trend. In order to be able to do so it is necessary to have a shoe last in which the toe end is removable for replacement by another.

The invention also contemplates means whereby, according to the same principle, and within limits the size or length of the shoe last may be increased or decreased by inserting or removing gap filling portions between the removable toe portion and the remainder of the last.

For reasons of geometrical convenience, it is found that the best location for the junction plane between the interchangeable toe portion and the remainder of the last is a plane across the widest portion of the overall last and tilted so as to be as nearly normal to the surface of the last at the top and bottom central portions thereof.

2

The separable toe and main body portions of the last are joined together in perfect registry with respect to one another through a kind of mortise and tenon arrangement and preferably through such an arrangement wherein there is only one mortise and one tenon having matching profiles of irregular geometry to ensure that one will fit precisely in the other in only one way; in order to lock the two together there is provided a screw through the main body portion and the mortise and tenon joint, the screw being freely rotatable within the main body portion and threading into the toe portion so as to exert enough pull to hold the latter firmly in position in front of the former.

A better understanding of the invention will be had from the following description of a preferred embodiment thereof, reference being had to the accompanying drawing of same wherein:

FIG. 1 is a longitudinal vertical cross-section through a shoe last embodying the present invention;

20 FIG. 2 is a cross-sectional view taken on line 2—2 of FIG. 1;

FIG. 3 is an exploded perspective view of the front half of a shoe last presenting a further embodiment of the invention;

25 FIG. 4 is a longitudinal cross-section view of same taken on line 4—4 of FIG. 3.

In FIG. 1, there is shown an embodiment wherein the invention is applied to a shoe last having a relatively low arch such as might be used in the manufacture of low to medium height heel shoes. The last proper is composed of three basic parts: a heel portion 1, a main body portion 2 and a toe or front end portion 3. The heel portion 1 is connected to the main body portion 2 through transverse cylindrical articulation 4. The last is shown closed in FIG. 1. The pin members 8 and 9 of the respective heel and main body portions are aligned in a plane passing below the axis of the articulation when the last is closed and above the said articulation when the last is open; a biasing spring 10 spanning across between pins 8 and 9 and exerting pull thereon toward the articulation. The spring 10 and pins 8 and 9 are located in appropriately formed longitudinal slots 11 and 12 in the heel and the main body portions of the last respectively.

The massive plastic main body and toe portions 2 and 3 respectively are formed by molding and incorporated therein at the time of molding are some metallic plugs or dowels 15 and 16 respectively. The plugs 15 and 16 have exposed oppositely facing ends in which are respectively formed the mortise cavity 20 and matching tenon projection 21 or vice versa.

Bolt 22 extends through bore 23 in the main body portion and the threaded end thereof consecutively engages and projects through the plugs 15 and 16. It is seen in FIG. 2 that the transverse cross-sectional profile of the matching mortise cavity 20 and tenon projection 21 are identically shaped and of irregular geometry so that one may fit accurately in the other in only one way.

The bolt 22 has a head 24 which is counter-sunk in the enlarged diameter portion 27 of the bore. Bolt 22 also has a shank portion 25 which is freely rotatable in the unthreaded part 26 of the bore within the mass of the plastic composition of the main body portion 2 of the last.

The plugs 15 and 16 are anchored in the respective masses of the molded material of the toe and the main body portions of the last; for this purpose there may be formed in the surfaces thereof which are contacting the molded plastic material some projections such as for instance peripheral ribs 30 and 31. In FIG. 3 there is shown an arrangement which is equivalent to that of FIG. 1, except that it applies to a raised arch type of last such as might be used in the production of high heel shoes;

the foregoing description of FIG. 1 would apply to FIG. 3 and for this reason the corresponding parts of FIG. 3 bear the same reference numerals as in FIG. 1.

The difference between the embodiment shown in FIG. 1 and the embodiment shown in FIG. 3 is that in the former the bore 23 extends rearwardly and upwardly to open at the rear of the main body portion of the last and above the articulation 4 whereas in the latter the bore 23' extends horizontally and rearwardly to open centrally in the sole surface of the main body portion of the last and under the axis of the articulation. 10

I claim:

1. In a molded shoe last, a heel portion connected to a main body portion and a toe portion removably and rigidly connected to said main body portion, said toe portion being connected to said main body portion according to a plane extending across the widest part of the last, a set of matching mortise and tenon formed in oppositely facing surfaces of the toe and main body

15 portions in said plane, said matching mortise and tenon having matching transverse profiles of irregular geometrical configuration, a bore through said main body portion projecting across said plane centrally of said mortise and tenon and coaxially extending for a short distance in said toe portion, releasable bore engaging means in said bore for interlocking said toe portion and main body portion, and wherein said mortise and tenon are formed in plugs of metal respectively disposed in said toe and main body portions and embedded therein at said surfaces.
